16 Claims. (Cl. 57—34)

This invention provides improvements in or relating to textile processes and machines. The invention comprises a process for treating thermoplastic yarn comprising the step of advancing the yarn in contact with a surface moving with the yarn and heating the yarn at the surface. Said surface and/or means adjacent to said surface may impart heat to the yarn.

The surface may be curved, and may comprise the peripheral surface of a roller. The yarn may be wrapped one or more times around the roller. The surface may comprise the surface of a belt.

The yarn may be simultaneously in contact with said surface and a second surface. One surface may comprise a peripheral surface of a roller and the second surface may comprise a surface of a belt running over the roller, the yarn passing between said surfaces.

Both surfaces may comprise peripheral surfaces of rollers.

The yarn may be subjected to pressures between the surfaces. When rollers are used, they may be nip rollers, and the yarn may touch the nip rollers only at the nip of the rollers.

In the process, the yarn may be twisted or false twisted. The surface may comprise a twist stop.

Yarn may be in a twisted or an untwisted state while in contact with and while heated at the surface.

The process may comprise control of the heat imparted to the yarn at the surface.

The invention also comprises apparatus for treating thermoplastic yarn comprising a movable surface in contact with which yarn can be advanced, and means adapted to heat the yarn at the surface. Said movable surface may comprise the periphery of a roller or of a belt.

The apparatus may comprise two movable surfaces between which yarn can be advanced. The surfaces may be adapted to exert pressure on a yarn between them, which pressure may be adjustable.

The apparatus may comprise a roller of which the peripheral surface is adapted to be heated by means located beneath said surface. Said heating means may be electrical.

Processes and apparatus for treating thermoplastic yarn according to the invention will now be described with reference to the accompanying drawings in which:

FIGURE 1 is a diagrammatic illustration of the apparatus.

FIGURE 2 is an axial section through a pair of nip rollers of the type which may find use in the apparatus of FIGURE 1, and

FIGURE 3 is a diagrammatic illustration of a roller and belt arrangement.

The apparatus illustrated in FIGURE 1 comprises a pair of nip rollers 11, 12, one of which may be a driven roller and the other an idler, which withdraw yarn 13 over a stabilizer 14 from a supply package

2

15. The nip rollers are heated by electrical resistance heating elements 16. The elements 16 are energised under the control of control 17 which includes temperature regulating means for maintaining a constant temperature at the nip rollers 11, 12, a temperature-sensing thermoelement 18 sensing variations in the temperature and actuating the control means 17 so as to compensate automatically for such variations. The thermoelement 18 can be adjusted so as to pre-select a desired temperature at the nip rollers 11, 12.

19. Yarn 13 coming from the nip rollers 11, 12 passes through a false-twisting device 19, the false twist imparted by this device running back only as far as the nip of the rollers 11, 12. The yarn 13 cools in the cooling zone 21 (which may be simply an air space at room temperature). From this it will be clear that the twist is imparted while the yarn is hot, and that the yarn is subsequently cooled. The yarn 13 untwists after passing the false-twisting device 19 and is forwarded by rollers 22, with a desired underfeed or overfeed, to wind-up means consisting of a package 23 which is rotated at constant peripheral speed by contact with a driving roller 24.

20. Various arrangements may be made for passing the yarn 13 over the rollers 11, 12. For example, the yarn may touch the rollers only at the nip. However, the heat thus imparted to the yarn 13 may not be sufficient for all desired treatments (although it will be sufficient for certain treatments) and the yarn may then be wrapped 25 around a portion of the periphery of each or either roller. Certain advantageous effects are to be secured thereby. For example, if the yarn is wrapped around a portion of the periphery of one roller before it passes through the nip, then, depending of course on the amount 30 of wrap, the temperature of the roller and the yarn tension, the yarn may be subjected to heat treatment before the insertion of twist. If the yarn is wrapped after passing through the nip, it is treated for a longer period, but there may be a tendency for some twist to be 35 "stopped" on the roller surface if the pressure of the yarn on the surface and/or the amount of wrap are too high. The yarn may, again, be wrapped one or more times completely around the periphery of each or either roller, and in one such arrangement may be led 40 away from the surface of a roller and through a tensioner before returning to the surface of the roller, whereby the temperature of the yarn may undergo a temporary change, and/or the tension in the yarn may be 45 altered. While these variations have been discussed with reference to the process as hereinbefore described, it will be readily apparent that they may be adapted to other processes which fall within the scope of the invention as set forth in the appended claims, for example, to processes in which yarn is treated without false-twisting, such as crimping processes of the stuffing-box 50 type and of other types.

55. The nip rollers are shown in greater detail in FIGURE 2. The lower roller 25 is driven by a gear wheel 26, and is mounted on roller bearings 27 for rotation on a hollow shaft 28. The upper roller 29 is mounted on a self aligning ball bearings 31 for rotation on a second hollow shaft 32.

60. The shaft 32 is urged toward the shaft 28 by non-illustrated means utilising, for example the weight of the roller 29 or extra weighting or resilient loading means.

The loading means may be adapted to apply any desired constant load which can be pre-selected for treating a particular material.

The rollers 25, 29 are of hollow construction, comprising side walls 33 joined by a peripheral wall 34 which has good heat conducting properties, preferably a metal such as stainless steel.

Carried fixedly on each shaft 28, 32, and located, respectively, in each roller 25, 29, are disc-like supporting members 35 which carry at their peripheries circular electrical resistance heating elements 36, the current-carrying wires 37 for which lie in grooves 38 provided in the members 35, and these wires 37 are led out of the interiors of the rollers 25, 29, through the hollow shafts 28, 32.

FIGURE 3 illustrates an arrangement comprising a roller 41 which may be generally similar to either of the rollers shown in FIGURE 2, including electrical heating means 42. A belt 43 passes over part of the peripheral surface 44 of the roller 41 and over a pair of further rollers 45 and a tensioning roller 46. The rollers 45 may be urged against the surface 44 by spring or other means (not shown) to exert pressure on a yarn 47 passing between the belt 43 and the surface 44. The yarn may pass over only that part of the surface 44 which is engaged by the belt, or it may pass over a greater part, or it may be wrapped one or more times around the periphery of the roller 44. This arrangement may be substituted in the apparatus shown in FIGURE 1, for the nip rollers 11, 12.

A single roller without a co-operating belt, which may be similar to the rollers above described, may be used for the process according to the invention, the yarn being wrapped around its periphery to an extent depending upon the heating effect required. A single movable belt surface with or without co-operating rollers may be used. The belt may be heated on its run in contact with the yarn or on a run on which the yarn does not contact the belt, by passing through a zone in which heat is imparted to the belt from an external source, or by heating means contained within the belt itself.

A textile machine may comprise a plurality of apparatus as hereinbefore described located side by side, the heating of the moving surfaces being controlled by a common pre-settable device and the temperature at each moving surface being compared with and adjusted to that of a master potentiometer.

It will be apparent that many modifications to the processes and apparatus according to the invention may be made without departing from the spirit and scope of the appended claims.

What I claim is:

1. A method of producing false-twisted thermoplastic yarn, comprising the steps of advancing the yarn along a predetermined path; heating the yarn by passing the same into contact with a heated surface moving with the yarn so that said yarn is heated without substantial friction between said yarn and said heated surface engaging and moving with the yarn and simultaneously the engagement between said yarn and said heated surface prevents any false-twist imparted to the yarn after heating to run back beyond said heated surface; and thereafter false-twisting the yarn while the same is in heated state.

2. A method of producing false-twisted thermoplastic yarn, comprising the steps of advancing the yarn along a predetermined path; heating the yarn by passing the same into contact with a heated curved surface moving with the yarn so that said yarn is heated without substantial friction between said yarn and said heated surface engaging and moving with the yarn and simultaneously the engagement between said yarn and said heated surface prevents any false-twist imparted to the yarn after heating to run back beyond said heated surface; and thereafter false-twisting the yarn while the same is in heated state.

3. A method of producing false-twisted thermoplastic yarn, comprising the steps of advancing the yarn along a predetermined path; heating the yarn by passing the same into contact with a heated surface which is continuously angularly displaced in direction of the advancement of moving with the yarn so that said yarn is heated without substantial friction between said yarn and said heated surface engaging and moving with the yarn and simultaneously the engagement between said yarn and said heated surface prevents any false-twist imparted to the yarn after heating to run back beyond said heated surface; and thereafter false-twisting the yarn while the same is in heated state.

4. A method of producing false-twisted thermoplastic yarn, comprising the steps of advancing the yarn along a predetermined path; heating the yarn by passing the same between and into contact with two opposed heated surfaces moving with the yarn so that said yarn is heated without substantial friction between said yarn and said opposed heated surfaces engaging and moving with the yarn and simultaneously the engagement between said yarn and said opposed heated surfaces prevents any false-twist imparted to the yarn after heating to run back beyond said opposed heated surfaces; and thereafter false-twisting the yarn while the same is in heated state.

5. A method as defined in claim 1; and further comprising the step of regulating the temperature of said heated surface within predetermined limits.

6. A method as defined in claim 1; and further comprising the step of cooling the yarn after false-twisting thereof.

7. A method as defined in claim 6; and further comprising the step of untwisting the yarn after cooling thereof.

8. Apparatus for producing false-twisted thermoplastic yarn from a supply of yarn, comprising yarn forwarding means for forwarding the yarn along a predetermined path; yarn take-up means arranged downstream of said forwarding means for receiving the yarn; yarn-heating means arranged intermediate said forwarding means and said take-up means and comprising a movable heated surface arranged in such path so as to be contacted by the yarn and being movable therewith so that said yarn is heated without substantial friction between said yarn and said heated surface engaging and moving with the yarn and simultaneously the engagement between said yarn and said heated surface prevents any false-twist imparted to the yarn after heating to run back beyond said heated surface; and false-twisting means arranged intermediate said heating means and said take-up means for imparting a false-twisted to the yarn while the yarn is in heated state from contact with said surface.

9. Apparatus as defined in claim 8, wherein said surface is adapted to be continuously displaced in direction of advancement of the yarn.

10. Apparatus as defined in claim 8, wherein said surface is adapted to be continuously rotatably displaced in direction of advancement of the yarn.

11. Apparatus as defined in claim 10, wherein said yarn-heating means comprises at least one roller, and wherein said surface is a peripheral surface of said roller.

12. Apparatus as defined in claim 9, wherein said yarn-heating means comprises at least one endless turning belt, and wherein said surface is a surface of said belt.

13. Apparatus as defined in claim 8, and further comprising an additional surface provided on said yarn-heating means and opposing said surface, and wherein the yarn advances between said surface and said additional surface.

14. Apparatus as defined in claim 13, wherein said surfaces engage the yarn and exert pressure thereon.

15. Apparatus as defined in claim 14, and further comprising means for adjusting said pressure.

16. Apparatus as defined in claim 13, wherein said heating means comprises a pair of nip rollers, said sur-

faces respectively constituting the peripheral surfaces of said nip rollers; and wherein said surfaces engage the yarn and exert pressure thereon.
